(57) **CLAIM**

The ornamental design for a frother, as shown and described.

DESCRIPTION

FIG. 1 is a perspective view of the frother with the cap on in accordance with the present invention;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side elevation view thereof;
FIG. 7 is a right side elevation view thereof;
FIG. 8 is a top perspective view of the frother with the cap off in accordance with the present invention;
FIG. 9 is a bottom perspective view thereof;
FIG. 10 is an alternate bottom perspective view thereof;
FIG. 11 is second alternate bottom perspective view thereof;
FIG. 12 is a front elevation view thereof;
FIG. 13 is a rear elevation view thereof;
FIG. 14 is a top plan view thereof;
